UNITED STATES PATENT OFFICE.

AARON F. RANDALL, OF WASHINGTON, DISTRICT OF COLUMBIA.

OIL-GAS GENERATOR.

SPECIFICATION forming part of Letters Patent No. 367,844, dated August 9, 1887.

Application filed August 19, 1886. Serial No. 211,232. (No model.)

To all whom it may concern:

Be it known that I, AARON F. RANDALL, a citizen of the United States, residing in the city of Washington, in the District of Columbia, have invented a new and useful Improvement 5 in Apparatus for Generating Gas from Liquid Hydrocarbons for Heating and Illuminating Purposes; and I do declare that the following is a full, exact, and clear description of the invention, which will enable others skilled in the art to which it appertains to make and use the same.

My invention relates to that class of oil-gas-generating apparatus which consume oil as a fuel, in which the oil is subjected to heat, and thereby vaporized or converted into gas before arriving at the point where ignition and combustion take place, whereby an apparatus may be so constructed that the heat produced 20 by the combustion of the gas from the oil decomposed in one part of it may be utilized in vaporizing and decomposing so much of the oil as enters another section of the apparatus, and from it may be conveyed into a common 25 gas-receiving chamber provided with suitable burners, in which it may be consumed in heating the apparatus, or it may be conveyed by a pipe into a gas-holder, where, after the admixture of the proper quantity of atmospheric 30 air, it may be conveyed to any desired point in a pipe for use for illumination or other purposes. This improved apparatus can be used for heating purposes when not desired for the manufacture of gas for illumination, or for 35 both purposes at the same time. In converting the distillates of petroleum into vapor or gas it is requisite, in order that the best results may be secured, to first vaporize the same by the application of heat, and then to subject 40 such vapors to a much higher degree of heat. This mode of procedure insures a uniform and complete conversion of the oil into gas, and yields the latter in the condition best adapted for economical use for heating and illuminating 45 purposes.

The object of my invention is to provide a safe, simple, and inexpensive construction of retorts and burners embodying this principle of operation, and which shall be adapted for 50 ready and convenient application to any or-

dinary stoves, ranges, furnaces, and grates of ordinary construction, such as are used for heating and cooking.

The invention consists of an improved construction of retorts and burners and of certain 55 novel combinations of parts composing the same, which will be first described in the following description, and then pointed out in the claims at the close of this specification.

In the accompanying drawings, Figure 1 is a 60 perspective view of the exterior of one form of my apparatus complete, with these several parts appertaining thereto in their respective places. Fig. 2 is a view in elevation of the same, with one of the retorts or gas-heating chambers 65 partly in section. Fig. 3 is a vertical transverse sectional view on line *x* in Fig. 2. Fig. 4 is a plan view of the base portion thereof, with the flange around the outer edge of the upper side of the same forming the drip or fire pan. Fig. 70 5 is a plan view of the tops of the retorts or gas-heating chambers, and shows the fire-spaces between the same. Fig. 6 is an end view of the gas generating and heating retorts. Fig. 7 is a view of the exterior of a vaporizing 75 chamber. Fig. 8 is a view of the oil-supply pipe covered with asbestos and wire-netting. Fig. 9 is a view of that part of the oil-supply pipe within the vaporizing-chamber. Fig. 10 is a side view of one of the caps or end pieces 80 into which the open end of the vaporizing-chamber is screwed. Fig. 11 is a view of the inner side of one of said caps. Fig. 12 is a similar view of the exterior of the same. Fig. 13 is a plan view of the upper side of the deflector-plate, and Fig. 14 is a view in cross-section of the piece fitting the opening *D* in the deflector-plate *D*. Fig. 15 is a longitudinal vertical section through one of the 85 passages in the neck connecting the generator 90 with the gas-receiving chamber.

The apparatus shown in Figs. 1, 2, 3, 5, and 6 is substantially of an oblong rectangular shape, and is adapted to be used in stoves, furnaces, or ranges having interior fire-spaces 95 of similar form; but the same may be made circular or of any other suitable form, and adapted to use in those stoves, ranges, or furnaces which have fire-spaces of corresponding form, so that the apparatus may fit snugly and 100

properly within the fire-space and rest upon the grate or bottom of the stove, furnace, or range.

When intended for generating gas for both heating and illuminating purposes, the apparatus is constructed with two or more gas-heating retorts or chambers, A, Figs. 1 and 2, and also shown in Figs. 3, 5, and 6. Each gas-heating retort or chamber has its own vaporizing-chamber, (shown at H in Figs. 2, 3, and 7,) 10 each in like manner formed of a shell, r, and is closed at one end and is screw-threaded externally at the open end, upon which the cap E (shown in Figs. 2, 5, 6, 10, 11, and 12) is screwed. This cap E is provided on its inner side with a ring or projection, u, Fig. 11, screw-threaded upon its interior and exterior sides, as shown in Fig. 10. Each of the caps E is also provided with an opening (shown by 15 the dotted lines w in Fig. 2, and in full lines in Figs. 6, 11, and 12,) through it, which is also screw-threaded to receive the oil-supply pipes f and f'.

The vaporizing-chambers H and the gas-heating retorts A may be made cylindrical, square, elliptical, or otherwise in cross-section, and as convenience or other considerations may suggest.

The gas-heating retorts or chambers A are 20 placed in close proximity to each other, as shown in Figs. 3 and 5, with a narrow space between them, as shown at P in Figs. 3, 5, and 6, to permit of the passage of the products of combustion, and at the same time in order that 25 all portions of the walls or shells thereof may be subjected to the heat. They may be constructed with walls J, Figs. 1, 3, 5, and 6, extending across this space between them, and vertically from the lower to the upper sides at 30 the ends thereof, thus forming a flue or flues between them, as shown at P in Fig. 5. These end walls extend upward for a sufficient distance above the tops of the gas-heating retorts or chambers, and are provided with 35 shoulders Q, so as to form supports upon which the ends of the deflector-plate D are to rest. These supports and shoulders Q are shown in 40 Figs. 1, 3, 5, and 6, and the upper portions of the extensions of the walls J enter notches Q', Fig. 13, in the ends of the deflector-plate D, 45 and serve to retain it in position.

The deflector-plate resting upon the shoulders Q forms a flue above the gas-heating retorts or chambers, which conveys the products of combustion around the adjacent and upper sides of the gas-heating retorts or chambers. The deflector-plate D is provided with an opening, D', directly over the flue P, extending longitudinally, and a movable piece 55 (shown by D'', Fig. 14) is fitted thereto, by which the opening D' may be closed, but which may be removed when necessary to permit of the passage through it of the products of combustion. The shell of the vaporizing-chamber H may conveniently be formed tubular, with the inner end closed in any suitable manner. It is screw-threaded externally at

the open end, and has numerous small holes, o, Figs. 2 and 7, for the passage of the oil-vapors generated within the same outwardly 70 into the gas-heating retort or chamber H.

The oil-supply pipe may be surrounded by some porous non-combustible material—such as fibrous asbestos, mineral wool, closely-coiled iron or steel wire, iron or steel filings or turnings, or other suitable material—preferably with a space between this material and the inner wall of the generating-chamber. When fibrous non-combustible material is employed, it is usually inclosed in a wire-netting, 75 O, (see Fig. 8,) which serves to retain it in its proper place. This porous non-combustible material distributes the oil passing from the oil-supply pipes uniformly and in finely-divided portions to the exterior of the 80 packing, and thus produces a steady and even vaporization of the oil. The flow of vapors through the openings o in the shells or walls of the vaporizing-chambers is thus made steady and continuous, avoiding all pulsations of the 85 flames at the burners K. These pulsations are 90 common in all ordinary burners, and are caused by the irregular vaporization of the oil when flowing in limited quantity from the supply-pipe directly against the heated surfaces of the 95 vaporizing chambers. The shells a a of the gas-heating retorts or chambers A A are each 100 closed at one end, and at the other end are provided with an orifice, z z, Fig. 2, screw-threaded, and closed by the cap E, as shown in Figs. 2 and 6. These openings are of sufficient 105 size to permit the passage through them of their respective vaporizing-chambers H H. When the vaporizing-chambers H H are 110 screwed into the flanges u of the caps E, the latter are then screwed into the openings z z, and the exterior of the walls of the vaporizing-chambers are maintained at proper distances 115 from the interior surfaces of walls of the gas-heating retorts or chambers, thus forming narrow spaces x' between them. (See x' in Figs. 2 and 3.) Each of the oil-supply pipes f f' enters 120 its vaporizing-chamber through a screw-threaded opening, w, in each cap E, and extends for a sufficient distance within the vaporizing-chamber, and has numerous small 125 openings, o', Fig. 9, along that portion within the vaporizing-chamber, to permit the escape of the oil therefrom. It is closed at the inner end, as shown at l, Fig. 9, and is connected with a common oil-supply pipe, f', Fig. 1, which in turn communicates with the oil-reservoir G, Fig. 1, which is suitably disposed above the level of the gas-heating retorts A. These pipes are provided with valves g g' g'', 130 of any suitable kind, to regulate the flow of oil through them.

C, Figs. 1, 2, 3, and 6, is a short supporting tube or leg, which is preferably made square in cross-section, except at the lower end, where it is rounded and screw-threaded, as shown in Figs. 3 and 6, and is screwed into an opening N, Fig. 4, in the top of the gas-receiving chamber B, and serves to support the gas-heating 135

chambers A. This tube or leg, where two generator-chambers are used in one apparatus, is provided with two passages, as shown at M and M', which extend its entire length, and 5 each of which communicates with the interior of a gas-heating retort or chamber at its upper end, and at the lower end with the interior of the gas-receiving chamber B. The connection between the gas-heating chamber and the gas-receiving chamber may consist of one or more 10 necks, each containing one or more passages, or they may be simply tubes or pipes, and any desired number may be employed. One of 15 these passages is provided with a valve, c', Fig. 3, by which communication through the same between the gas heating chamber and the gas-receiving chamber is controlled. It is also provided with a second opening, c², between the valve c' and the gas-heating retort, which 20 is screw-threaded and receives the end of pipe i, which communicates with the gas-holder F, or to other burners. Valve g³ in pipe i controls the passage of gas through pipe i. The 25 passages M and M' enter the shells of their respective gas-heating retorts or chambers at the lowest point of their inner surfaces, and that portion of each of these passages within the walls of the gas-heating retorts, and as far as may be necessary outwardly, is made narrower in its vertical cross-section than in its longitudinal cross-section, as shown at g in Fig. 30 2. This tube or leg C may extend upward, as shown at t, between the adjacent walls of the gas-heating retorts, and serves to form a partition, dividing the fire-space P into two flues, P P, and may be extended upward as far as the tops of the gas heating retorts.

40 *c* is a rib or lug on the side of leg *C*, provided with the opening *d*, through which the oil-supply pipe *h*, which forms the auxiliary burner, passes, and serves to hold the same in a firm position.

B in Fig. 1 is the gas-receiving chamber, into which the gas from the gas heating retorts A passes through the passages M and M' in the supporting leg C, and it is provided with suitable educts or openings (shown at l) upon its upper side or elsewhere in its walls, as may be preferable. These openings or educts are provided with suitable burners, as shown at k, to insure the perfect combustion of the gas as it escapes therefrom.

55 Around the outer edge and upon the upper side of the gas-receiving chamber is a raised rim of sufficient height, forming a drip-pan, (shown at L,) which serves to catch and retain any overflow of oil from the auxiliary burner *h*.

In the drawings, Fig. 2, the burners are represented as being of the kind known as the "Bunsen burner;" but I may use any other of a suitable kind.

n is a raised portion or boss upon the upper side of the center portion of the gas receiving chamber to add thickness to that portion of its shell, and it is provided with the opening *N*, which is screw-threaded to receive the screw-threaded end of the supporting tube or

leg C. The dotted lines $p^2 p^3$ in Fig. 6 show the outer and inner surfaces of the shells or walls of the gas-heating retorts A.

J J indicate the end walls between the gas-heating retorts A, uniting them, and which serve to form the ends of the flues or fire-spaces P.

In Fig. 2 the dotted lines q show the inner 75 surface of the gas-heating retort A, r the shell of the vaporizing chamber H, and s the walls of the oil-supply pipe f , and the relative positions of the said several parts to each other when the vaporizing-chamber, together with 80 its oil-supply pipe, is in its proper positions.

x, between the dotted lines *q* and *r*, indicates the narrow space between the outer surface of the vaporizing-chamber and the inner surface of the gas-heating retort, into which the vapor of the oil passes on its escape from the vaporizing-chamber. 85

e is the open space between the upper surface of the gas-heating retort A and the deflector D, as shown in Figs. 2, 3, and 6. 90

I proceed as follows to use my apparatus: The oil reservoir being supplied with liquid hydrocarbons, preferably the lighter distillates of petroleum, the valves $g' g'$ are first 95 opened and a quantity of the oil is introduced

opened and a quantity of the oil sufficient to fully saturate the packing within the vaporizing-chamber is permitted to flow through pipes f and f' . These valves are then closed to cut off the supply of the oil in order to prevent flooding the vaporizing-chamber when valve g^2 is opened to permit the oil to flow into pipe h . The oil issuing from the openings o^2 in pipe h is then ignited and the flames therefrom surround the gas heating retorts A 105 A, heating them and the vaporizing-chambers H to such a degree that the oil with which the packing within the latter is saturated is vaporized. The vapor makes its way out of the vaporizing-chambers through the openings 110 in the chamber walls, diffusing

o o in the shells or walls, and fills the narrow spaces *x* between the exterior surfaces of the vaporizing chambers *H* and of the interior surfaces of the gas-heating retorts *A A*, being thereby spread out into a thin stratum and uniformly subjected to the action of the heated surfaces of the shells of the gas-heating retorts *A A*. The gas escapes from the gas-heating retorts through the passages *M* and *M'* in the

reigns through the passages M and M' in the tube or leg C , passing downward through said passages into the gas-receiving chamber B , and thence into the burners K , where it is ignited by the flames issuing from the openings o^2 in pipe h . As soon as the gas issuing from the burners K is ignited, valve c^2 is closed.

from the burners K is ignited, valve g' is closed to cut off the flow of the oil into pipe h , and valves g g' are opened. The supply of oil to the vaporizing-chambers is controlled by these valves g and g' , the flames of the gas issuing from the burners K, playing against the lower part of the outer surfaces of the gas-heating retorts or chambers A. A, one portion following the outer surfaces of the exterior walls outwardly and upward, and another portion pass-

ing upward through the flues P P, around the adjacent walls of the gas-heating retorts until, striking the deflector D, they are forced outwardly over the upper surfaces of the gas-heating retorts, and are distributed and divided, as may be desired. By the removal of piece D² of the deflector-plate D that portion of the flames passing upward through the flues P P is permitted to pass through the opening to D' in the deflector-plate.

When it is desired to manufacture gas for purposes of illumination, or for any other purpose, I proceed as stated above until a good supply of gas is escaping from the gas-receiving chamber through the burners, when valve g' in pipe i is opened and valve e' in the supporting tube or leg C is closed, and the flow of the gas from one of the gas-heating retorts A into the gas-receiving chamber B is cut off and conveyed through pipe i to other burners, or into the gas-holder F; when it is mixed with the proper quantity of atmospheric air, which is forced into the gas-holder, and thence conveyed through pipes to the place desired for use.

The gas-holder F is provided with an air force-pump of any suitable kind, by means of which the requisite quantity of atmospheric air may be forced into the same for admixture with the gas formed from the decomposed vapors of the liquid hydrocarbons to properly prepare the latter for illuminating purposes.

Having thus described my invention and its method of operation, what I claim as new, and desire to secure by Letters Patent, is—

1. The combination, with a generator-chamber, of an oil-supply pipe extending within said chamber, the part within said chamber being perforated, and a stratum of fibrous or porous non-combustible material interposed between the supply-pipe and the inner walls of the generator-chamber, space being left between said non-combustible material and the inclosing walls, substantially as described.

2. The combination, with a generator-chamber, of an oil-supply pipe extending into said generator-chamber, the part within said chamber being perforated, and a gas-heating chamber wholly inclosing the generator chamber, substantially as described.

3. The combination, with a generator-chamber, of an oil-supply pipe extending within the same, the part within the said chamber being perforated, a stratum of asbestos surrounding the perforated portion of said pipe, and a wrapping of wire-gauze around the asbestos, substantially as described.

4. The combination, with two generator-chambers, of an oil-supply pipe for each chamber, a gas-heating chamber inclosing each generator-chamber, with a space between them, a burner beneath the gas-heating chambers connected therewith, and a deflector-plate above the gas-heating chambers, substantially as described.

5. The combination, with two gas-generating chambers and a gas-receiving chamber be-

low the same, of a neck or necks connecting the gas-generating chambers with the gas-receiving chamber, provided with a separate passage for each generator-chamber, substantially as described.

6. The combination of two gas-generator chambers, a gas-receiving chamber beneath the same, a separate passage connecting each generator-chamber with the gas-receiving chamber, one of said passages being provided with a valve, a gasometer, and a pipe connecting the gasometer with the passage above the valve, substantially as described.

7. A burner having a vaporizing-chamber, an oil-supply pipe opening into the same, a gas-heating chamber inclosing the same, a gas-receiving chamber located beneath the gas-heating chamber and having gas-ducts in its upper side, and a passage communicating with said gas-heating chamber and said gas-receiving chamber, substantially as described.

8. A burner having a vaporizing-chamber, an oil-supply pipe opening into the same, a gas-heating chamber inclosing the same, a gas-receiving chamber located beneath the gas-heating chamber and having gas-ducts in its upper side, and a passage communicating with said gas-heating chamber and gas-receiving chamber, and a flame-deflecting plate above said gas-heating chamber, substantially as described.

9. The combination, with vaporizing-chamber H, having the opening o o in its walls, an oil-supply pipe opening into the same, of the inclosing gas-heating chamber A and the gas-receiving chamber B, having the gas-ducts l in its upper side and communicating with said gas-heating chamber, substantially as described.

10. The combination, with the vaporizing-chamber H, having the openings o o, an oil-supply pipe extending within the same and having perforations in that portion within the vaporizing-chamber, of the inclosing gas-heating-chamber A, the gas receiving chamber B, communicating with said chamber A and having openings l on its upper side, and the deflector-plate D above the gas-heating chamber A, substantially as described.

11. The combination, with the vaporizing-chamber H, having openings o o, an oil-supply pipe extending within the same, having perforations o' in that portion within the vaporizing-chamber, and the same portion being surrounded by a fibrous non-combustible material inclosed in a netting of wire-gauze, the inclosing gas-heating chamber A, a tube or leg, C, and the gas-receiving chamber B, having the openings l, of the pipes f and h, having valves g and g', substantially as described.

12. The combination, with the vaporizing-chamber H, having openings o o, the inclosing gas-heating chamber A, a tube or tubes, C, the gas-receiving chamber B, having openings l, and the deflector-plate D, of the pipes f and h, substantially as described.

13. The combination, with a generator-cham-

ber, of an oil-supply pipe extending within the same, the part within said chamber being perforated, a stratum of asbestos or other suitable fibrous or porous non-combustible material surrounding the perforated portion of said pipe, a wrapping of wire-gauze around the asbestos or other fibrous non-combustible material, a gas-heating chamber inclosing said gas generating chamber, a gas-receiving chamber having openings therein provided with suitable burners located beneath the gas-heating chamber, a tube or tubes communicating between said gas-heating and the said gas-receiving chambers, a deflector-plate above the gas-heating chamber, and pipes *f* and *h*, having valves *g* and *g'*, substantially as described.

14. The combination, in an oil-burner, of two generator-chambers, each having an oil-supply pipe within the same, the parts of said 20 oil-supply pipes within the said chambers

being perforated, a stratum of asbestos or other suitable fibrous non-combustible material surrounding the perforated portions of said pipes, a wrapping of wire-gauze around the said asbestos or other fibrous non-combustible material, a gas-heating chamber inclosing each gas-generator chamber, a gas-receiving chamber having openings therein provided with suitable burners, and located beneath the gas-heating chambers, a supporting tube or leg having passages communicating between said gas-heating chambers and the said gas receiving chamber, one of such passages or tubes being provided with a valve, and pipes *f*, *f'*, and *h*, having valves *g*, *g'*, and *g''*, substantially as described. 25 30 35

AARON F. RANDALL.
